[57] CLAIM

The ornamental design for a hand-held cordless, grass-/weed trimmer, as shown and described.

DESCRIPTION

FIG. 1 is a top, front and right side perspective view of a hand-held cordless grass/weed trimmer showing my new design;

FIG. 2 is a front and left side perspective view thereof, the right side being a mirror image of that shown;

FIG. 3 is a top plan view thereof;

FIG. 4 is a rear elevational view thereof; and

FIG. 5 is a bottom plan view thereof.

FIG.1**FIG.2**FIG.3
